UNITED STATES PATENT OFFICE.

GEORGE S. VAN VOORHIS, OF BROOKLINE, MASSACHUSETTS.

MEANS FOR ISSUING DIRECTIONS CONCERNING CARE OF MOTOR-VEHICLES.

1,077,657.

Specification of Letters Patent.

Patented Nov. 4, 1913.

Application filed January 25, 1913. Serial No. 744,257.

To all whom it may concern:

Be it known that I, GEORGE S. VAN VOORHIS, a citizen of the United States, residing at Brookline, Massachusetts, have invented certain new and useful Improvements in Means for Issuing Directions Concerning Care of Motor-Vehicles, of which the following is a specification.

My present invention has for its object to provide means for giving directions to the user or operator of a motor car concerning the care of the same in such a manner as to insure everything being done at suitable intervals and in proper order, and nothing overlooked.

As is well known to the users of motor cars, these require attention in their various parts, entirely according to mileage. For example, all parts of the running gear need oiling or grease cups screwing down with every hundred miles; the transmission and differential need refilling at the end of every five hundred miles or thereabout, the gasoline tank after mileage depending on the capacity of the tank, and so on through the long list of things to be done about a car, including cleaning out carbon and grinding valves, washing out oil from crank case, testing tires, etc., which are so essential but so liable to be overlooked or delayed.

My invention consists broadly in providing means for issuing a printed strip of directions which at the close of the day or trip or proper time as indicated by the mileage, may be removed and its directions followed, thus insuring that everything necessary about the car has been attended to.

The invention also includes the novel features of construction and arrangement and combination of parts hereinafter described and particularly defined by the appended claim.

An embodiment of my invention is illustrated in the accompanying drawing in which—

Figure 1 is a plan view of one form of a device for accomplishing the above described purposes, the cover being removed. Fig. 2 is a sectional elevation.

Referring by reference characters to this drawing, the numeral 1 designates a suitable metal case having means such as bracket 2 for securing it to the dash or other appropriate part of the car. The case is preferably of substantially cylindrical shape and is adapted to receive a roll of paper of tape

form, indicated at 3, upon which the directions referred to are printed *seriatim*, access to the case for insertion of a fresh roll being permitted by a door or cover 1 hinged at 1.

In order to draw the paper from the roll at a rate commensurate with the travel or mileage of the automobile, I provide a pair of feed rolls 4 and 5, one of which is driven by the ordinary flexible shaft used to operate the speedometer or odometer. In the drawing I have illustrated the roll 4 as driven through a worm and worm wheel connection from the shaft or spindle 6, which at one end is adapted for connection with the flexible shaft indicated at 7 and at the other end may be adapted for attachment to the speedometer as at 8. The tape will of course be printed with suitable directions and in proper order according to the make of car for which it is designed and at the end of a suitable distance, say at the end of a hundred mile run, the operator will remove the portion of the tape which has been fed by the rolls and proceed to care for the machine according to the directions printed thereon, checking off each thing as done, and, when through, filing the strip away for record, if desired.

In order to facilitate the removal of the projected portion of the strip a severing knife may be provided as indicated at 9. In order to support the paper roll in proper position within the case and in such manner as to permit the paper being drawn therefrom by the feed rolls, the paper will be preferably mounted on a spool 10 at one end of the case provided with a fixed pin 11 for engaging the corresponding end of the spool, the other end of the spool being supported by a spring pressed pin 12 provided on the outside of the case with a handle 13 by which it may be withdrawn for the removal and insertion of the spool. When a fresh roll is being inserted the end of the paper will be first inserted in the bite of the feed rolls 4 and 5 and the lower roll 5 turned by the handle 5 until the paper is gripped between the rolls and thereafter the paper roll inserted in place and the case closed when the device is ready for use.

In addition to having the directions for the care of the car printed on the tape, it may also have the mileage printed thereon so that each strip or part of the tape removed at the end of the trip will serve as a trip indicator.

My device as above described, is of great value to the operator of pleasure cars as it removes all chance of failure to care for the various parts of the car at the proper time, but it is of special value in connection with business wagons, taxicabs, trucks, etc., where the driver seldom, if ever, takes care of the car. In such cases all the driver would have to do in turning the car into the garage is to hand the strip of directions to the garage foreman.

Having thus described my invention what I claim is:—

In combination a suitable case, a roll of

paper or tape therein having printed thereon ¹⁵ *seriatim* directions for the care of a motor vehicle, feed rolls driven by the movement of the vehicle for delivering said tape from the case as the vehicle progresses, and means for effecting severance of the withdrawn ²⁰ portions.

In testimony whereof I affix my signature in presence of two witnesses.

GEORGE S. VAN VOORHIS.
